UNITED STATES PATENT OFFICE.

MATTIE MARTIN, OF GILROY, CALIFORNIA.

SHOPPING BAG OR PARCEL HOLDER.

Application filed March 17, 1924. Serial No. 699,953.

To all whom it may concern:

Be it known that I, MATTIE MARTIN, a citizen of the United States, and a resident of Gilroy, in the county of Santa Clara and 5 State of California, have invented certain new and useful Improvements in Shopping Bags or Parcel Holders, of which the following is a specification.

The invention relates particularly to a 10 shopping bag or parcel holder, the principal object of which is to provide a parcel holder or shopping bag for a machine (automobile) and is to be attached to the robe rod usually found on the rear of the front seat of touring 15 cars, sedans and other motor vehicles, and yet will not interfere with robes in any way.

It is one object of my invention to provide 20 a parcel holder that may be readily mounted upon the robe rod of any type or make of car and which is neat in appearance and one which will not injure the car in any way.

It is another object of my invention to provide 25 a device of the character indicated that will occupy but a small amount of space when full or empty and yet be capable of accommodating a large number of parcels.

It is still another object of my invention 30 to provide a device of the character indicated that is so constructed as to present a smooth exterior surface throughout the front, rear and bottom, these parts being made from a single piece of material, and that will be simple in construction, economical to manufacture, strong, durable, and 35 highly efficient in its practical application, and owing to its V shape will not interfere with the comfort of occupants of the car.

In the drawing:

Figure 1 is a perspective view of the de- 40 vice.

Figure 2 is a vertical transverse section through the same.

Figure 3 is an enlarged vertical transverse section through the bottom of the holder.

45 Referring more particularly to the drawing, I show at 1 a bar pivotally mounted at 2 to the back of an automobile seat 3 by means of arms 4.

At 5—5 and 6—6 are shown steel arms, 50 each pair being spaced by wood bars of equal length at their tops and bottoms as indicated at 7—7 and 8—8. The parts 7—7—5—5 and parts 8—8—6—6 form two rectangular frames as shown. The bottom members 7 55 and 8 are rounded as shown and pivotally connected by hinges as 10. This construc-

tion provides a framework over which are mounted front and rear portions of heavy cardboard or similar material as shown at 11—11.

60 Mounted on the inner surfaces of portions 11—11 is a canvas strip 12, extending the full length of the holder and effectually preventing anything from dropping down between bottom bars 7 and 8 when the holder is opened.

65 The ends of the frame are closed by means of suitable V-shaped flexible material 14, reinforced at its upper edge by a tape 15, the degree to which the device may be 70 opened being determined by the length of the upper edges of these side pieces 14.

75 From the foregoing it may be readily seen that the holder is in the form of a large V-shaped pocket when open, and forms a thin flat container when closed, its thickness when closed being determined by the combined thicknesses of the front and rear elements of the framework.

To the upper rear cross bar 8 are secured 80 buckles and straps as at 16 by means of which the device is fastened to bar 1, and at 17 is shown a strap and buckle fastener for the device when closed. Pockets 18 are arranged within the holder by mounting a 85 strip of canvas 19 on the inner rear surface.

This shopping bag or parcel holder is 90 preferably made sufficiently large for its lower edge to rest upon the floor of the car, but since the front and rear are hinged directly together at the bottom it takes up but little room, even when full, and interferes in no way at any time with the comfort of 95 occupants of the car.

I am aware that prior to my invention 95 other shopping bags or parcel holders have been made. I therefore do not claim such broadly, but

I claim:

100 A shopping bag or parcel holder comprising a pair of frames of uniform size hinged together along their opposed bottom edges, a covering for each of said frames, V-shaped flexible elements connecting the opposed side portions of said frames, a flexible strip arranged in said holder above the bottom elements of the frame to form a bottom therefor, and means arranged on one of said frames for securing the same to the robe rod 105 of a motor car.

MATTIE MARTIN.
